UNITED STATES PATENT OFFICE.

HENRY SHAFFER, OF IDA, MICHIGAN.

TALKING-MACHINE OR THE LIKE.

1,384,409.

Specification of Letters Patent. Patented July 12, 1921.

Application filed April 6, 1918. Serial No. 227,041.

To all whom it may concern:

Be it known that I, HENRY SHAFFER, a citizen of the United States, residing at Ida, in the county of Monroe and State of Michigan, have invented certain new and useful Improvements in Talking-Machines or the like, of which the following is a description.

My invention belongs to that general class of devices known as talking machines, phonographs or the like, for recording or reproducing music, lectures, addresses or the like, and relates particularly to a machine in which the same may be operated for the recording or reproducing so as to make possible a long, continuous, audible performance of sounds without any unnatural or undesired pause between different records. The invention has among its objects the production of a machine of the kind described which may be employed in recording or reproducing sounds upon or from one or more record disks, cylinders or the like, which device is simple, convenient, durable, dependable, efficient and satisfactory for use wherever found applicable. It has particularly as an object the production of an automatically controlled machine of the kind described which will accurately operate to produce the desired result without depending upon the skill of the operator. The device is particularly designed for recording upon suitable records the desired sounds which may be produced while moving pictures are being taken, as well as a device which will reproduce the sounds in conjunction with the displaying or reproducing of the pictures which have been taken, so that a more life-like or natural performance may be produced, and talking or sounds may be reproduced in synchronism with the pictures and continuously therewith. The same is also suitable for the playing of dance music, operas, etc. Many other objects, advantages and uses of the apparatus herein shown and described will be obvious to those skilled in the art from the disclosure herein given.

To this end, my invention consists in the novel construction, arrangement and combination of parts herein shown and described and more particularly pointed out in the claims.

In the drawings, wherein like reference characters indicate like or corresponding parts,

Figure 1 is a plan view of my preferred machine partially shown diagrammatically;

Fig. 2 is a view in elevation taken substantially on line 2-2 of Fig. 1 of a portion thereof;

Fig. 3 is a sectional view taken substantially on line 3-3 of Fig. 5;

Fig. 4 is a sectional view taken substantially on line 4-4 of Fig. 1;

Fig. 5 is a sectional view taken substantially on line 5-5 of Fig. 6;

Fig. 6 is a plan view enlarged of a portion of one of the records and switch members shown in Fig. 1;

Fig. 7 is a view in elevation of connecting mechanism between the record carriers;

Fig. 8 is a view in elevation of a modified arrangement of the records and carriers;

Fig. 9 is a view in elevation of a modified construction in which the controlling is done mechanically rather than electrically;

Fig. 10 is a view in elevation of the same; and Fig. 11 is a sectional view taken substantially on line 11-11 of Fig. 10.

Referring to the drawings, it may be mentioned that I have shown two types of apparatus for carrying out the invention, one being electrically controlled and operated and the other mechanically. Figs. 1 to 7 illustrate the electrically controlled apparatus, and Figs. 9 to 11 the mechanical, Fig. 8 showing an arrangement which may be adopted with either type of controlling apparatus. Heretofore machines have been produced embodying a plurality of records from which the reproducing element, or elements are successively placed into operation to prevent a stopping of the machine when a single record has been played, but as far as I am aware, it has never been proposed to drive the record support continuously at the same rate of speed so as to produce the proper sound when the transmitting mechanism for one record is brought into operation. Where the machines are arranged so that one record stops and another simultaneously starts there is a variation in speed due to the stopping and starting, and the least variation in the speed of the rotating records while changing from one record to the other causes a change in the pitch or tone reproduced. This, however, is a fatal defect in connection with moving pictures as the particular sound produced must come at the right time or the result may be a laughable farce, detracting from the picture, or from the story, music, lecture or what-

ever it might be. It is also undesirable in the case of dance music or operas. With my improved apparatus the records are played or made in succession, one after another, 5 one stopping at the end and the other simultaneously taking it up and continuing without a break, giving a continuous effect as if one record were employed regardless of whether two or an infinite number of records are employed. With my machine herein described both records are traveling at the same speed at the time of the disengagement of one transmitting mechanism with its record, and the engagement of the other 10 transmitting mechanism with its record. I have referred to the records as being played or that is reproduced, but in recording matter on a record that is to be reproduced, this original sound is recorded by means of a 15 recorder, and the trade has generally termed this as recording, the same occurring in the manufacture of the records. By the term "reproducing," however, I wish to be understood as including producing or reproducing of the original sound on the record and recording it, as well as the reproduction of the same from the record in the sense generally understood. I might also mention that I have illustrated a disk type of apparatus 20 as this is the type most generally used, but the invention in its broadest sense is applicable for any type of machine whether the records to be made or to be played are disks, cylinders, rolls, strips or 25 bands or the like.

While the apparatus may be in the form of two machines associated and coupled up by connecting my controlling mechanism, I generally prefer to provide a machine 30 arranged to carry a plurality of records and provided with a plurality of sound transmitting mechanisms, whether recorders or reproducers, and driving mechanism that will operate the record carriers in unison or 35 successively. While the machine may be equipped to handle any desired number of records, two is ordinarily sufficient as the operator can change one record while the other is playing, but there is no limit to the 40 number of mechanisms which may be associated and arranged to control each other in succession or in a predetermined manner. Referring particularly to Figs. 1 and 3, in which one type of apparatus is shown, 1 45 represents a suitable base, as for instance a cabinet or casing which may itself contain the horn or sound gathering or dispensing apparatus. Mounted on the base are the 50 rotatable record carriers 3 and 5 which are 55 adapted to carry the records where the records are of the disk type. The carriers are 60 adapted to be rotated or driven by the shafts 6, and these may be driven by a common shaft 7, intermediate gearing 8, or 65 equivalent means for the purpose. Shaft 7

may be driven by main shaft 10, operated by a suitable source of power and connected to shaft 7 by gearing 11 or its equivalent. I provide clutch mechanism 9 so that either shaft may be driven or stopped at will. It 70 is considered unnecessary to describe in detail any driving mechanism, as obviously this is a matter of preference.

Mounted above the carriers 3 and 5 are the tubular or tone arms 12 and 13, or their 75 equivalent, each carrying or co-operating with the sound transmitting mechanism 15, which in the case of a reproducer carries the needles 16. This particular part of the apparatus may be as desired, and I have 80 illustrated a type of arm and diaphragm of well known type. These are shown connected with a common horn tone part of flue 14, it being understood that this may be of the desired construction. In this case the arms 85 12 and 13 are mounted on 14 so that they may swing in the usual manner. The disks 2 and 4 may be of the desired shape, size and construction, and in the particular type of apparatus shown in Figs. 1 to 7, I have 90 shown the same provided with a hole 18, so that electrical contact members when mounted on the carriers, may be arranged above the disk and arranged to co-operate with the arm when it reaches the end of its 95 travel. The hole has an additional advantage as it necessitates the accurate positioning of the record on its support in such manner that one record may continue through the other without a break or overlap. The 100 switch shown, there being one for each record (see Figs. 3, 5 and 6), consists of a pair of preferably resilient or yielding arms 19 and 20, having contacts 26, which are adjustably mounted on arms 21 and 22, 23 105 being adjusting screws by means of which the device may be adjusted for engagement with the arms 12 or 13 at the desired point. The arms 21 and 22 are pivotally secured at 24 to a support 25, so that they may be 110 turned up in inserting or removing the record, and are each electrically connected as will be hereafter described. The switch just described and the particular apparatus illustrated is intended to release and set in 115 action supports under the arms 12 or 13 as the case may be. Arranged near the outside of each carrier is shown a bracket 27, which carries a movable support member 28, or its equivalent arranged to carry the arm 120 12 or 13 with the needle 16, or its equivalent, off the record when that particular part of the apparatus is not in operation. In the electrically controlled apparatus part 28 is arranged to be controlled by an arm 29 125 which is engaged at 30 and actuated by an electric magnet 31, or equivalent means for the purpose.

Referring to Fig. 5, the carrier 3 (it being understood that carrier 5 is similarly 130

constructed) carries rings 32 and 33, which are operatively or electrically connected with the switch members 21—22 and their extending parts 19 and 20, the two rings and switch parts being insulated from each other. Contact members or brushes 34 and 35 may be provided, the same being normally maintained in operative contact by springs 36 or their equivalents. The contact members 34 and 35 are electrically connected by conductors 37 and 38 with the mechanism shown in Fig. 4 for the opposite disk as is most clearly shown in Fig. 1, in which the wiring is shown substantially diagrammatically.

I also prefer to provide automatically controlled means for lifting each of the arms 12 and 13 to a position where the needle will not engage the record when the same reaches the end of its travel and closes the adjacent switch between the points 26. As most clearly shown in Figs. 1 and 2, 40 represents an arm or bracket which carries an electric magnet 39, the same being so arranged that the arm is lifted at the end of its travel and substantially simultaneously with the releasing or dropping of the other arm in engagement with the other record. I also provide, in the case illustrated, two drops or electrically controlled switches consisting of the magnets 45 and 45', which are provided with the drop members 46' and locking members 46 therefor. These are similar to the well known types of relays or enunciator stops, and are therefore not shown in detail as the construction is obvious to those skilled in the art.

There may be employed any suitable source or sources of electrical energy, but for the purpose I have shown batteries 42 and 52, two batteries being shown to avoid confusion and make the circuits clear. Referring to Fig. 1, conductor 38, extending from one disk, connects one side of the magnet 31 arranged to control the arm coöperating with the opposite disk. For clearness I shall assume that magnet 31 is energized, drawing member 28 to a position to release the transmitter 15 on arm 12, the arm 13 being held as shown. The opposite side or the other conductor to the magnet referred to 41 is connected with the battery 42, conductor 37 is connected with drop 45, and this by conductor 44 with the battery. A conductor 50 connects with drop 45' which is connected by conductor 47 with one of the rings on the other disk, and the other ring thereat is connected by conductor 48 with the magnet 27, which is in turn connected by conductor 51 with the battery 42. 53 is a conductor connected with a switch contact member 54, connecting the same with battery 52, and this is connected through conductor 56 with magnet 39 arranged above disk 2. A conductor 55 connects this mag-

net 39 with the contact 55'. Drop 45' has contacts 58 and 60 which are connected by conductor 59 with the magnet 39 above disk 4, and conductor 57 with battery 52. This magnet is connected by conductor 61 with the battery 52 through conductor 56 or its equivalent.

Assuming as mentioned that arm 12 is in a position so that the needle engages the disk, the same traveling as usual toward the center of the rotating disk, as soon as the same comes in contact with the switch part 20 arranged above that disk, a circuit is closed as follows: 38, magnet 31 adjacent the disk 4, 41, battery 42, conductor 44, drop 45, 37 and through the switch 38, closing the circuit, causing magnet 31 at disk 4 to be energized to release arm 13, and causing 46' of the drop 45 to close the circuit between contacts 54 and 55'. A circuit is thereupon formed as follows:—46', 54, 53, battery 52, conductor 56, magnet 39 above disk 2, conductor 55, contact 55' and 46'. This causes magnet 39 above disk 2 to be energized so that arm 12 is raised substantially as shown in Fig. 2, lifting the needle 16 out of engagement with the disk 2. In the meantime, while the arm 13 is traveling to move the reproducer toward the center of the disk, record 2 may be changed and a new record positioned, arm 12 being returned to the position indicated by the full lines in Fig. 1, the same being supported by 28. As soon as arm 13 reaches a point to close the switch 19—20 above disk 4, a circuit may be traced as follows:—19, 48, 31 (at disk 2), 51, 44, battery 42, 50, 45', 47 and to the ring connected with one of the parts of the switch. This immediately causes arm 12 to be released and drop 46' of 45' bridge contacts 58 and 60, so that a circuit may be traced:—46', 60, 59, magnet 39 above disk 4, 61, 56, battery 52, 57, 58 and 46'. This raises arm 13 out of operation. Another record may then be substituted in place of disk 4. It will be seen from the preceding that simultaneously with the raising of the arm 13, for example the arm 12 is dropped and continues until it is raised and the other arm again dropped, there being sufficient time between the playing of a record for a new record to be positioned. In positioning a new record the switch described and shown in Fig. 3 may be turned up so as to permit the removal and positioning of the record.

In Fig. 8, the records and mechanisms are shown as arranged one above the other, the results being the same. In the mechanical control construction shown in Figs. 9, 10 and 11, 66 and 67 represent records and 68—69 arms carrying the transmitting mechanisms 71. 73 represent suitable brackets which carry members 74. One member 74 is connected by rod 72 with the pin 71 130

through a link 72'. The other member 74 is connected by link 65 with the pin 71' supporting arm 68. A bell-crank 76-77, or the equivalent, is suitably mounted on the carrier above the disk, and is of such construction that as a record and its carrier engages the needle or other part carried by the transmitter, 70, the transmitter and the tone arm carrying it will move toward the center and 10 the needle will engage 77. This will operate 77-76, which will partially rock member 75, operating the rod 65 or 72 as the case may be so as to release the arm 68 or 69, as it may be. With this construction I 15 have shown no means for lifting the arm to a point where the needle will not engage the record. This may be done by the operator, or suitable means provided for the purpose.

Referring to Fig. 1, I have shown switches 20 62 and 63 which may be arranged at a remote point, and which may be connected by conductors 64 and 65 in the desired manner. As illustrated, the switches 62 and 63 may be arranged to be controlled by the operator 25 of the moving picture machine or they may be arranged to be automatically controlled by the moving picture machine itself. It will be obvious that the phonograph herein described may be started at such time as the 30 operator of the moving picture machine desires, or as the particular picture requires. The switches S may be arranged at the phonograph so that the record changer can control the machine if necessary.

35 By the word "record" as used in the specification and claims I wish to be understood as meaning a cylinder, roll, disk plate or other article of rubber, wax, paper, metal or other substance, which is to be or has been 40 perforated, indented or otherwise prepared so as to reproduce sound, such as speech, vocal or instrumental music, etc., when brought into contact with certain apparatus, as the stylus, needle, point or the like of a phonograph, etc. Also by the words "sound transmitting mechanism" or "reproducing means", I wish to be understood as including any mechanism arranged to coöperate with the record, said mechanism in the 45 trade in one case being termed a recorder and in the other a reproducer, the recorder being the instrument for preparing the record and the reproducer the instrument for reproducing the sound from the prepared 50 record.

Having thus described my invention, it is obvious that various immaterial modifications may be made in the same without departing from the spirit of my invention, 60 hence I do not wish to be understood as limiting myself to the exact form, construction, arrangement and combination of parts herein shown and described or uses mentioned.

What I claim as new and desire to secure 65 by Letters Patent is:—

1. In a machine of the character described, a plurality of associated record carrying mechanisms, means common to both of said carrying mechanisms for simultaneously driving the same, a plurality of sound transmitting mechanisms arranged to coöperate with the records carried by said carrying mechanism, in combination with operable means disposed within the path of travel of the transmitting mechanism for controlling 70 said transmitting mechanisms whereby the same singly and successively coöperate with the records in a desired manner.

2. In a machine of the character described, a plurality of associated record carrying mechanisms, sound transmitting mechanisms arranged to coöperate with the records carried by said carrying mechanisms, means for rotating said carrying mechanisms, in combination with means for controlling said 80 transmitting mechanisms whereby the same coöperate with the records, one at a time, said means including a controlling element arranged upon each carrying mechanism adapted to pass through apertures in the 85 record to be engaged by an element carried by the transmitting mechanisms.

3. In a machine of the character described, record carrying mechanisms for a plurality of independent records, of a sound transmitting mechanism for each carrying mechanism in combination with means for automatically controlling said transmitting mechanisms whereby they are singly and successively placed in operation, said means 90 including a contact on each record carrier located well within the periphery thereof and adapted to coöperate with the transmitting mechanism for controlling said mechanism.

4. In a machine of the character described, the combination with a plurality of record carriers, driving means for operating said carriers at the same rate of speed, transmitting means arranged to coöperate with and engage the records on said carriers, means for automatically controlling said sound transmitting means, whereby when one transmitter reaches the end of a record the same will be lifted from operative relation 110 therewith, and the other transmitter will be simultaneously moved into operative association with another record.

5. In a machine of the character described, a plurality of rotatable record carriers, 120 driving means for operating said carriers, independent transmitters arranged to coöperate successively with the records on said carrier, means for automatically controlling said transmitters, whereby one transmitter 125 is lifted from its record at a given time and another transmitter placed into operative association with its record, said controlling means including controlling elements projecting through apertures in the record and 130

adapted to coöperate with means carried by the transmitter.

6. In a machine of the character described, a plurality of record carriers, independent sound transmitters, adapted to engage records carried by said carriers, means for successively placing said transmitters into operative association with the record, said means comprising controlling switches disposed well within the periphery of each record carrier and adapted to be controlled by said transmitters, circuits and electro-magnets controlled by said switches for simultaneously placing one transmitter in position on its record while lifting a second transmitter from its record.

7. In a talking machine of the kind described and in combination, a plurality of associated rotatable record carriers and means for simultaneously driving the same, a tone arm for each carrier, each tone arm provided with sound transmitting mechanism arranged to coöperate with the record mounted on and movable with its respective carrier, means for supporting each of said arms with the transmitting mechanism out of engagement with the records, controlling means for each of said supporting means, said controlling means having mechanisms arranged to coöperate with the tone arms when the same have traveled a predetermined distance, whereby one arm is automatically released and its sound transmitting mechanism becomes effective on the rotating record when the other arm has reached the limit of its travel, and coöoperating mechanism for controlling said last mentioned other arm to lift the needle carried thereby out of engagement with its rotating record simultaneously with the engagement of the one effective needle carried by the other arm with its record, whereby one transmitting mechanism will become inoperative simultaneously with the other one becoming operative.

8. In a machine of the character described, the combination with a plurality of record carriers, and means for rotating said carriers, of transmitters for each record carried by said carriers, automatically acting means

for placing one transmitter into operative relation with its record, and to simultaneously remove the other transmitter from association with its record, said means including a plurality of electro-magnets coöoperating with the transmitters, and controlling switches disposed near the axis of each record carrier, and adapted to be engaged during the movement of the transmitters, substantially as described.

9. In a machine of the character described, the combination with a plurality of record carriers, and means for rotating said carriers, of transmitters for each record carried by said carriers, automatically acting means for placing one transmitter into operative relation with its record, and to simultaneously remove the other transmitter from association with its record, said means including a plurality of electro-magnets coöoperating with the transmitters, and controlling switches disposed near the axis of each record carrier, and adapted to be engaged during the movement of the transmitters, the controlling switches passing through apertures in the record and having pivoted portions adapted to lie parallel with the surface of each record when in an operative position.

10. A machine of the character described, comprising a plurality of record carriers, and driving means for rotating said carriers, a transmitter for each carrier, means acting automatically for simultaneously lifting one transmitter from its record, and placing another in operative association with its record, said means including controlling switches and electro-magnets, supports for the magnets, said magnets overlying the transmitters and adapted to be energized to raise a transmitter and deenergized to permit a transmitter to drop in contact with its record.

In testimony whereof, I have hereunto signed my name in the presence of two subscribing witnesses.

HENRY SHAFER.
